LASTING MACHINE

Lloyd G. Miller, Beverly, Mass., assignor to
United Shoe Machinery Corporation, Flemington, N. J., a corporation of New Jersey

Application November 17, 1945, Serial No. 629,527

26 Claims. (Cl. 12—1)

1

This invention relates to machines for use in the manufacture of shoes, and particularly to improvements in lasting machines of the type disclosed in an application for United States Letters Patent Serial No. 593,981, filed on May 16, 1945, in the name of Corwin W. Baker, and also in United States Letters Patent No. 2,397,369, granted on March 26, 1946, on an application of Edward Quinn and Napoleon A. Monfils. It is to be understood, however, that features of this invention are not limited necessarily in their utility to use in machine organizations of the exact type shown in the mentioned application and patent.

In these prior machines, the shoe is fed along continuously and the stock to be lasted is progressively tensioned, in a direction substantially perpendicular to the bottom of the shoe, and then drawn inwardly from the edge of the shoe bottom and toward lasted position, by means of the frictional drag imposed by a driven roll, against the operating surface of which the lasting margin of the stock is held yieldingly by a pressure member. As the lasting margin leaves the roll and pressure member, it is immediately wiped inwardly from the edge of the shoe bottom and pressed firmly into lasted position against the bottom of the shoe by means of a wiper having a continuous inwiping action with the result that the lasting margin of the stock which, in some cases together with the shoe bottom, has been rendered adhesive, is effectively secured in lasted position.

It is an object of this invention to provide an improved lasting machine of the above-mentioned type having novel means for continuously wiping inwardly the lasting margin of the stock, after it has been tensioned and drawn in over the bottom of a shoe, and for pressing the lasting margin firmly against the bottom of the shoe. To this end, the herein illustrated machine, which has means for tensioning the stock lengthwise of a shoe, drawing its lasting margin inwardly over the bottom of the shoe and for feeding the shoe, is provided with wiping means comprising a rotary disk having a peripheral working surface formed by a plurality of circumferentially disposed, axially offset, helical ribs for wiping the stock inwardly from the edge of the shoe bottom and for pressing it against the bottom of the shoe. Preferably these helical ribs have rounded leading ends for imparting hammer-like blows to the lasting margin, to augment the pressing action in causing adherence of the lasting margin to the shoe bottom, and these ribs are so arranged that

5 the leading end of each rib is in substantial axial alignment with the trailing end of the next preceding rib, so that a circumferentially continuous wiping surface is presented to the lasting margin of the stock thus avoiding any tendency of the rounded leading ends of the ribs to break down the marginal edge of the shoe-bottom forming member and assuring a sharply defined feather line at this point. The lead of the helical ribs is such that when the disk is rotated at a relatively high speed each rib will sweep over the lasting margin in a direction extending inwardly, and obliquely to, the edge of the shoe bottom, so that the lasting margin will not only be wiped inwardly and pressed down against the shoe bottom, but also will be smoothed out lengthwise of the shoe and in the direction of feed.

10 In the machines disclosed in the above-mentioned application and patent, the lasting margin of the stock is held yieldingly against the operating surface of the friction roll by the pressure member at two locations, one at the edge of the shoe bottom and the other positioned inwardly therefrom, the function of the latter being 15 to cause the frictional drag imposed by the roll on the stock to have a component tending to draw the stock inwardly from the edge of the shoe bottom and toward lasted position. With the improved wiping means of the present invention, 20 the construction of the pressure member may be simplified by omitting that portion which presses the lasting margin against the roll at the point located inwardly from the edge of the shoe bottom and a side face of the wiper employed for 25 this purpose. With this arrangement, an additional frictional drag will be imposed on the lasting margin at this point by the rapidly moving side surface of the wiper and the tensioning and overdrawing effect of the friction roll thus augmented.

30 To facilitate the operation of the machine in lasting stock that is coated with adhesive in a non-tacky condition, such, for example, as precoated covers for platform shoes, another feature of the invention contemplates the provision of means for applying heat to the lasting margin of the stock as it is being tensioned and, with this purpose in view, the herein illustrated machine is shown provided with means for heating 35 a portion of the pressure member which is in direct engagement with the stock so that a coating of adhesive on the stock, which is in a non-tacky condition, will be activated and rendered tacky before the stock is wiped inwardly and 40 pressed against the shoe bottom by the wiper.

Similarly, the wiping action may, in accordance with a still further feature of the invention, be improved by the provision of means for heating the rotary wiper.

The above and other objects and features of this invention will become apparent from the following detailed description of the embodiment illustrated in the accompanying drawings and will be pointed out in the claims.

In the drawings,

Fig. 1 is a view in front elevation, with certain parts in section, of a machine embodying features of this invention;

Fig. 2 is a plan view of the operating elements of the machine shown in Fig. 1;

Fig. 3 is a plan view similar to that of Fig. 2, but with certain parts omitted for the sake of clarity and showing the operating parts in different positions;

Fig. 4 is a view of the machine similar to that of Fig. 3 and showing a slightly modified construction; and

Fig. 5 is a detail view of the improved wiper.

Referring to the drawings, the machine illustrated therein, which, with exceptions to be noted below, is similar to the machine illustrated in application Serial No. 593,981, referred to above, has a friction roll 10 for tensioning and overdrawing the stock the lasting margin of which is yieldingly pressed against an operating surface 11 of the roll, at two locations spaced circumferentially thereof, by means of a pressure member comprising a body portion 12 and a hinged part 14; a wiper, indicated by the reference character 16; an edge gage roll 18; and a shoe-bottom rest 20.

The roll 10 is mounted on the lower end of a shaft 30 which is journaled in a bearing block 32. This block has a T-shaped arcuate rib 34 which is slidably mounted in a correspondingly shaped groove 35 formed in a supporting bracket 36, Figs. 2 and 4. The bracket 36 is likewise provided with a T-shaped arcuate rib 38 that is slidably mounted in a correspondingly shaped groove 40 in a plate 42. As is explained in detail in the above-mentioned application, these arcuate grooves and ribs are so arranged as to permit the varying of the inclination of the shaft 30, together with the roll 10, without altering the vertical position of the roll, and clamping bolts 43 and 44 are provided for locking the bearing block 32 and bracket 36, respectively, after the roll has been adjusted. The plate 42 is secured to a slide 45 by means of a tongue 46 and groove 48 and clamping bolts 50 which pass through elongated slots 51 in the plate, see Fig. 2. When these bolts are loosened the roll may be adjusted toward or away from the wiper 16.

The slide 45 is supported in a guide bracket 52 which is secured to a frame member 54 that is mounted on the top of a column 56 of suitable height, Fig. 1. A cam roll 58, carried by the slide 45, runs in a cam groove 60 formed in a cam bar 62 which is mounted for vertical sliding movement in the bracket by means of a treadle, not shown, but connected thereto by a treadle rod 64. Such vertical movement of the cam bar 62 will shift the bearing block 36 and roll 10 forwardly or rearwardly of the machine for a purpose which will presently appear.

The shaft 30, and roll 10, are driven from a suitable source of power, not shown, through a main input gear 78 which meshes with an idler gear 76, Fig. 1. Formed integrally with the idler gear 76 is another gear (not shown) which meshes with a gear 82, secured by a setscrew 84 to a verti-

cal shaft 86 that is journaled in bearings 88 and 90 in a gear housing 72 carried by the frame 54. The gear 82 drives, through a reduction train comprising gears 92, 94 and 96, a shaft 98 that is likewise journaled in the housing 72 and which projects through its lower wall. This shaft is connected to the shaft 30, which carries the roll 10, by means of an extensible shaft assembly indicated by the reference character 100 and including universal joints 102 and 104. A sheet-metal guard housing 106 surrounds the extensible shaft 100, as shown in Fig. 1.

The body portion 12 of the pressure member is secured, by means of a bolt 110, to the lower end 15 of an arm 112 which is pivotally mounted on the bearings block 32 by means of a pin 114 that extends through flanges 116 in the bearing block, see Fig. 2. The bolt 110 extends through an elongated slot 118 in the body portion of the pressure member, Fig. 3, which, when the bolt is loosened, permits adjustment of the pressure member laterally of the machine and relatively to the roll 10. The hinged part 14 of the pressure member is pivotally mounted on the body portion 20 12 by means of a pin 120 and is yieldingly urged to swing in a counterclockwise direction, and toward the roll 10, about the pin 120, Fig. 3, by means of a compression spring 122 which is fitted in recesses 124 and 126 in the body portion and hinged part, respectively. A rod 130 having a spherical end 132 is connected to the arm 112 by a plate 134 and screw 136. This rod extends rearwardly of the machine from the arm 112 and passes through an aperture 138 in a bracket member 140 that is secured to the frame member 54. Interposed between a collar 144, adjustably secured to the rod 130 by a setscrew 146 and the bracket 140, is a compression spring 148.

When the treadle, not shown, is depressed, the 40 cam bar 62 will be moved downwardly, and the cam groove 60 is so shaped that, as a result of this downward movement of the cam bar, the slide 45, together with the roll 10, will be moved rearwardly of the machine from the position 45 shown in Fig. 3 to that shown in Fig. 2. As the slide and roll go back, the arm 112 will be swung about the pivot pin 114 by the action of the rod 130 and the spring 148 until the pressure member 50 nearly engages the roll, after which continued movement of the slide and roll will compress spring 148. For the purpose of preventing actual contact of the roll 10 on the pressure member, a stop screw 155 is provided, see Fig. 2, this screw 55 being so set as to engage the bearing block 32 and hold the pressure member spaced from the roll a few thousandths of an inch. Fig. 2 shows the roll and pressure member in the positions assumed when the treadle is thus depressed and with the lasting margin M of the platform cover 60 of a shoe S having a platform P pressed yieldingly against the operating surface 11 of the roll 10 by the spring 148. Upon release of the treadle, which will be elevated by a suitable spring, not shown, the cam bar is moved upwardly so that a 65 reverse action takes place; the pressure member following forward movement of the roll 10 which now occurs, until engagement of a collar 156 on the rod 130 with the bracket 140 arrests such forward movement. Thereafter the roll moves 70 away from the pressure member until the parts assume the positions shown in Fig. 3. The spring 122 is weaker and less effective than the spring 148 and the pressure member is so adjusted relatively to the roll that the hinged part 14 will 75 contact the lasting margin M just before the

fixed part 12 does. Thus spring 122 will be somewhat compressed when the parts are in the positions shown in Fig. 2 and the hinged part 14 will be moved away from an abutment surface 157 on the body portion 12 (Fig. 3).

The wiper 16, which is of novel and improved construction, comprises a relatively thin disk which is secured, by means of screws 180, to the end of a shaft 182 that is journaled in a bearing block 184 and which carries a belt pulley 186. The bearing block 184 is adjustably mounted, by means of bolts 187 and slots 188, on the lower end of a housing 190 that is mounted for angular adjustment about a boss 192 on the lower end of the housing 12, this boss being centered about the axis of shaft 86, and clamping bolts 184 are provided for holding the housing and wiper disk in adjusted position. The shaft 86 carries a bevel gear 193 which meshes with a bevel gear 194 mounted on a countershaft 196. Also mounted on the shaft 196 is a pulley 198 and a belt 200 runs over this pulley, the pulley 186 and an adjustable idler pulley 202.

The edge gage roll 18 is journaled on a stud 210 which is carried by a block 212 that is mounted for adjustment, forwardly and rearwardly of the machine, on an arm 218 by means of a clamping bolt 216 which passes through a slot 214 in the block, Figs. 2, 3 and 5. The arm 218 is likewise mounted for adjustment, laterally of the machine, by means of a clamping bolt 222 and slot 220 in a bar 224 and this bar is mounted for adjustment vertically of the machine on a slide 236, by means of a bolt 232 and a slot 234. The slide 236 is mounted for reciprocating movement in a guide bracket, not shown, but similar to the bracket 52 and secured to the frame 54. This slide is moved forwardly and rearwardly of the machine by the cam bar 62 when the treadle is operated in the same manner as slide 42, as is explained in detail in the above-mentioned application, Serial No. 593,981.

The bottom rest 20 is mounted on the bearing block 32, for angular adjustment about the axis of the roll 10, by means of an arcuate boss 240 on the bearing block and a bolt 242 which passes through a slot 244 formed in the upper end of the bottom rest, see Fig. 1.

The operating surface of the wiper 16 is formed by a plurality of circumferentially disposed, axially offset, helical ribs 300. The leading ends of these ribs are rounded, as indicated at 302, Fig. 5, and each leading end is substantially in axial alignment with the trailing end 304 of the next preceding rib so that a circumferentially continuous wiping surface is presented to the work, see Figs. 3 and 5, and one of the ribs is always in contact with the work. The effect of the rounded leading ends 302 as they strike the lasting margin is to produce a hammer-like blow which greatly augments the action of the wiper in causing adherence of the stock to the shoe-bottom member. However, by arranging the leading ends and trailing ends of the ribs in axial alignment, as above pointed out, any tendency for the rounded leading ends to strike and break down the edge of the shoe-bottom member, herein illustrated as a platform P, is avoided. The rounded leading ends are formed as continuations of semicircular recesses 306 formed in the side face of the disk.

The illustrated machine operates generally in the same manner as the machines of the application and patent mentioned above, and with the treadle depressed the lasting margin M of the stock is pressed against the operating surface 11

of the roll 10 by the portions 12 and 14 of the pressure member and, as a result of the frictional drag imposed on the stock by the roll, the stock is tensioned; its lasting margin drawn inwardly from the edge of the shoe bottom and over the bottom of the platform P, and the shoe is fed along, all as a continuous progressive operation. For increasing this frictional action, the operating surface 11 may be provided with a plurality of spaced projections, shown diagrammatically in the several figures of the drawings by crossed lines. As the stock emerges from between the roll and the portion 14 of the pressure member, see Fig. 2, it is immediately wiped inwardly from the edge of the shoe bottom and pressed firmly against the bottom of the shoe by means of the rapidly rotating wiping disk 16, the operating surface of which is composed of the plurality of helical ribs 300. Because of the direction of the lead of these ribs and the fact that the disk is rotated at a relatively high speed, these ribs sweep across the overdrawn lasting margin of the stock with a component of motion, extending lengthwise of the edge of the shoe and which is in excess of the feeding movement effected by the roll. Consequently, the ribs 300 not only wipe the stock inwardly from the edge of the shoe bottom but they also tend to smooth the stock out in a direction lengthwise of the shoe. This effect may be enhanced, to varying degrees, by swinging the housing 190 about the boss 192 so that the plane of the wiping disk intersects the edge of the shoe bottom at different angles, see Fig. 2. Thus, not only do the helical ribs smooth out wrinkles in the stock, but they also tend to assist in the feeding of the shoe by the roll.

As noted above, the rounded leading ends of the ribs produce a hammer-like effect which greatly facilitates the adherence of the stock to the bottom of the shoe, it being understood, of course, that either the lasting margin of the stock or the bottom of the shoe, or both, will have been rendered adhesive prior to the lasting operation, or at least before the lasting margin is pressed against the bottom of the shoe by the wiper. However, since the rounded leading ends are in alignment with the trailing ends, so that there is always one rib in contact with the work, there is no tendency for the rounded ends to break down or otherwise damage the edge of the platform P. As has already been suggested, the hinged portion 12 of the pressure member may be omitted and a side face of the wiping disk 16 utilized to hold the lasting margin of the stock against the operating face of the roll, and into frictional engagement therewith, at a point located inwardly from the edge of the shoe and an arrangement of this kind is shown in Fig. 4. In this view, the hinged portion 14 has been eliminated and the wiping disk 16 positioned somewhat closer to the roll. Also the disk is provided on one side with a smooth-faced plate 400 which, when the treadle is depressed to move the roll into the operative position shown, presses the lasting margin of the stock against the operating surface of the roll and into frictional engagement therewith. With this arrangement, the overdrawing effect of the frictional drag of the roll 10, which is obtained as a result of pressing the lasting margin against the roll at a point located inwardly from the edge of the insole, in a manner similar to that set forth in the aforementioned patent and application, is considerably augmented by the frictional drag that is also imposed on the outside face of the stock by the

moving surface of the plate 400, while the vertical tensioning effect of the roll is produced, as before, by the frictional drag of the roll on that portion of the stock which is pressed against its operating surface at the edge of the shoe bottom by the body portion 12 of the pressure member.

In the manufacture of certain types of platform shoes the platform covers are made from strip material the lasting margin of which is coated with adhesive in a non-tacky condition; also the adhesive which has been applied to the platform cover or other stock to be lasted may, in some cases, be permitted to dry for too long a period so that the adhesive reaches a non-tacky condition in which it will not adhere satisfactorily, if at all, to the shoe bottom member upon being wiped in and pressed down by the wiper. It has been found that by applying heat to the lasting margin of stock of this type during the lasting operation the adhesive may be rendered tacky and a satisfactory lasting job accomplished. For thus applying heat to the stock, in the construction shown in Fig. 4, the illustrated machine is provided with an electrical heating unit 500, which may be a conventional plug-type heating unit, that is press-fitted into a bore 502 in the body portion 12 of the pressure member. From this heating unit leads 504 and 506 extend to a suitable source of electrical energy, not shown. During the operation of the machine in lasting the stock, sufficient heat from the portion 12, that is heated by the unit 500 and which presses the lasting margin M against the roll 10, will penetrate through the stock and render tacky, i. e., activate, the adhesive coating on the inside face thereof. The degree of heating of the body portion 12 will be only sufficient to activate the adhesive and not enough to scorch or otherwise mar the outside face of the lasting margin of the stock and any suitable form of thermostatic control may be used properly to regulate the action of the heating unit 500. While the heating unit is herein illustrated as applied to the modified construction of pressure member in which the hinged part 14 has been omitted, it will, of course, be readily understood that a similar heating arrangement may be provided in the pressure members shown in Figs. 2 and 3 and which are provided with the hinged portion 14.

The action of the rotary wiper 16 in laying the overlasted stock smoothly down on the shoe bottom may be improved by heating the wiper. This may be conveniently accomplished in the manner shown in Fig. 4 in which a block 510 having a flat side face 512 and provided with an electrical heating unit 514 is adjustably mounted on the bracket 36, by means of a support 516, bolt 518 and slot 520, ear 522, and a clamping bolt 524, so that the side face 512 may be positioned close to the side face of the wiper. This heating unit, which is connected to a suitable source of electrical energy, not shown, by means of leads 526 and 528, will radiate sufficient heat to the closely adjacent wiper to keep the wiper itself warmed to a point where the helical ribs 300 will have a heated ironing action on the overlasted stock which is quite effective in smoothing the stock and removing wrinkles therefrom.

Having described the invention, what I claim as new and desire to secure by Letters Patent of the United States is:

1. A lasting machine having, in combination, means for continuously and progressively tensioning the stock to be lasted in a direction substantially perpendicular to the bottom of a shoe,

and means comprising a rotary disk having a peripheral working surface provided with a plurality of helical ribs for wiping the lasting margin of the stock inwardly from the edge of the shoe bottom, in the direction of rotation of the disk, and pressing it against the bottom of the shoe.

2. A lasting machine having, in combination, means for continuously and progressively tensioning the stock to be lasted in a direction substantially perpendicular to the bottom of a shoe, and means comprising a rotary disk having a peripheral working surface provided with a plurality of circumferentially disposed and axially offset helical ribs for wiping the lasting margin of the stock inwardly from the edge of the shoe bottom, in the direction of rotation of the disk, and pressing it against the bottom of the shoe.

3. A lasting machine having, in combination, means for continuously and progressively tensioning the stock to be lasted in a direction substantially perpendicular to the bottom of a shoe, and means comprising a rotary disk having a peripheral working surface provided with a plurality of circumferentially disposed helical ribs for wiping the lasting margin inwardly from the edge of the shoe bottom and pressing it against the bottom of the shoe, said ribs being axially offset and having rounded leading ends for imparting hammer blows to the lasting margin.

4. A lasting machine having, in combination, means for continuously and progressively tensioning the stock to be lasted in a direction substantially perpendicular to the bottom of a shoe, and means comprising a rotary disk having a peripheral working surface provided with a plurality of circumferentially disposed helical ribs for wiping the lasting margin inwardly from the edge of the shoe bottom and pressing it against the bottom of the shoe, said ribs being axially offset and having rounded leading ends for imparting hammer blows to the lasting margin, the leading end of each rib being in substantial axial alinement with the trailing end of the preceding rib so that a circumferentially continuous wiping surface is presented to the lasting margin of the stock.

5. A lasting machine having, in combination, means for continuously and progressively tensioning the stock to be lasted in a direction perpendicular to the bottom of a shoe and drawing the lasting margin of the stock inwardly from the edge of the shoe bottom and over the bottom of the shoe, and means comprising a rotary disk having a peripheral working surface provided with a plurality of helical ribs for wiping the lasting margin of the stock inwardly from the edge of the shoe bottom, in the direction of rotation of the disk, and pressing it against the bottom of the shoe.

6. A lasting machine having, in combination, means for continuously and progressively tensioning the stock to be lasted in a direction perpendicular to the bottom of a shoe and drawing the lasting margin of the stock inwardly from the edge of the shoe bottom and over the bottom of the shoe, and means comprising a rotary disk having a peripheral working surface provided with a plurality of circumferentially disposed and axially offset helical ribs for wiping the lasting margin of the stock inwardly from the edge of the shoe bottom, in the direction of rotation of the disk, and pressing it against the bottom of the shoe.

7. A lasting machine having, in combination, means for continuously and progressively tensioning the stock to be lasted in a direction perpen-

dicular to the bottom of a shoe and drawing the lasting margin of the stock inwardly from the edge of the shoe bottom and over the bottom of the shoe, and means comprising a rotary disk having a peripheral working surface provided with a plurality of circumferentially disposed helical ribs for wiping the lasting margin inwardly from the edge of the shoe bottom and pressing it against the bottom of the shoe, said ribs being axially offset and having rounded leading ends for imparting hammer blows to the lasting margin.

8. A lasting machine having, in combination, means for continuously and progressively tensioning the stock to be lasted in a direction perpendicular to the bottom of a shoe and drawing the lasting margin of the stock inwardly from the edge of the shoe bottom and over the bottom of the shoe, and means comprising a rotary disk having a peripheral working surface provided with a plurality of circumferentially disposed helical ribs for wiping the lasting margin inwardly from the edge of the shoe bottom and pressing it against the bottom of the shoe, said ribs being axially offset and having rounded leading ends for imparting hammer blows to the lasting margin, the leading end of each rib being in substantial axial alignment with the trailing end of the preceding rib to provide a circumferentially continuous wiping surface.

9. A lasting machine having, in combination, a driven roll and cooperating pressure member for engaging opposite sides of the lasting margin of stock to be lasted and so constructed and arranged as to apply lasting stress to said lasting margin for continuously and progressively tensioning the stock, for drawing the lasting margin inwardly from the edge of the shoe bottom and over the bottom of the shoe, and for feeding the shoe, and means comprising a rotary disk having a peripheral working surface provided with a plurality of helical ribs for wiping the lasting margin of the stock inwardly from the edge of the shoe bottom, in the direction of rotation of the disk, and pressing it against the bottom of the shoe.

10. A lasting machine having, in combination, a driven roll and cooperating pressure member for engaging opposite sides of the lasting margin of stock to be lasted and so constructed and arranged as to apply lasting stress to said lasting margin for continuously and progressively tensioning the stock, for drawing the lasting margin inwardly from the edge of the shoe bottom and over the bottom of the shoe, and for feeding the shoe, and means comprising a rotary disk having a peripheral working surface provided with a plurality of circumferentially disposed and axially offset helical ribs for wiping the lasting margin of the stock inwardly from the edge of the shoe bottom, in the direction of rotation of the disk, and pressing it against the bottom of the shoe.

11. A lasting machine having, in combination, a driven roll and cooperating pressure member for engaging opposite sides of the lasting margin of stock to be lasted and so constructed and arranged as to apply lasting stress to said lasting margin for continuously and progressively tensioning the stock, for drawing the lasting margin inwardly from the edge of the shoe bottom and over the bottom of the shoe, and for feeding the shoe, and means comprising a rotary disk having a peripheral working surface provided with a plurality of circumferentially disposed helical ribs for wiping the lasting margin inwardly from

the edge of the shoe bottom and pressing it against the bottom of the shoe, said ribs being axially offset and having rounded leading ends for imparting hammer blows to the lasting margin.

12. A lasting machine having, in combination, a driven roll and cooperating pressure member for engaging opposite sides of the lasting margin of stock to be lasted and so constructed and arranged to apply lasting stress to said lasting margin for continuously and progressively tensioning the stock, for drawing the lasting margin inwardly from the edge of the shoe bottom and over the bottom of the shoe, and for feeding the shoe, and means comprising a rotary disk having a peripheral working surface provided with a plurality of circumferentially disposed helical ribs for wiping the lasting margin inwardly from the edge of the shoe bottom and pressing it against the bottom of the shoe, said ribs being axially offset and having rounded leading ends for imparting hammer blows to the lasting margin, the leading end of each rib being in substantial axial alignment with the trailing end of the preceding rib to provide a circumferentially continuous wiping surface.

13. A lasting machine having, in combination, a driven roll, a cooperating member for pressing the lasting margin of stock to be lasted against the roll at a point adjacent to the edge of the bottom of a shoe so that the roll will apply a frictional drag on said lasting margin for continuously and progressively tensioning the stock heightwise of the shoe and for feeding the shoe, and a rotary wiper for continuously wiping the lasting margin inwardly from the edge of the shoe bottom and for pressing it against the bottom of the shoe, said rotary wiper being constructed and arranged relatively to the driven roll to press the lasting margin of the stock into frictional engagement with the driven roll, at a point located inwardly from the edge of the shoe bottom, to cause said driven roll also to exert a frictional drag on the lasting margin for drawing the tensioned stock inwardly from the edge of the shoe bottom before it is wiped inwardly and pressed against the shoe bottom.

14. A lasting machine having, in combination, a driven roll, a cooperating member for pressing the lasting margin of stock to be lasted against the roll at a point adjacent to the marginal edge of the bottom of a shoe so that the roll will apply a frictional drag on said lasting margin for continuously and progressively tensioning the stock heightwise of the shoe and for feeding the shoe, and means comprising a rotary disk having a peripheral working surface for continuously wiping the lasting margin inwardly from the edge of the shoe bottom and for pressing it against the shoe bottom, said disk having a flat side face for pressing the lasting margin against the roll at a point located inwardly from the edge of the shoe bottom so that the roll will also exert a frictional drag on the lasting margin for drawing the tensioned stock inwardly from the edge of the shoe bottom before it is wiped inwardly and pressed against the shoe bottom by said working surface.

15. A lasting machine having, in combination, a driven roll, a cooperating member for pressing the lasting margin of stock to be lasted against the roll at a point adjacent to the edge of the bottom of a shoe so that the roll will apply a frictional drag on said lasting margin for continuously and progressively tensioning the stock

heightwise of the shoe and for feeding the shoe, and means comprising a rotary disk having a peripheral working surface formed of a plurality of circumferentially spaced axially offset helical ribs for continuously wiping the lasting margin inwardly from the edge of the shoe bottom and for pressing it against the shoe bottom, said disk having a flat side face for pressing the lasting margin against the roll at a point located inwardly from the edge of the shoe bottom so that the roll will also exert a frictional drag on the lasting margin for drawing the tensioned stock inwardly from the edge of the shoe bottom before it is wiped inwardly and pressed against the shoe bottom by said working surface.

16. A lasting machine having, in combination, a driven roll, and a rotary wiper constructed and arranged relatively to the driven roll so as to press the lasting margin of stock to be lasted into frictional engagement with said driven roll at a point located inwardly from the edge of the shoe bottom, said wiper being rotated in a direction to cooperate with said roll to exert a pull on said lasting margin directed inwardly from the edge of the shoe bottom to overdraw said lasting margin and said wiper acting thereafter to wipe and press said overdrawn margin against the bottom of the shoe.

17. A lasting machine having, in combination, a driven roll, and a rotary wiper constructed and arranged relatively to the driven roll to press the lasting margin of stock to be lasted into frictional engagement with said driven roll at a point located inwardly from the edge of the bottom of a shoe to cause said driven roll to exert a frictional drag on the lasting margin in a direction inwardly from the edge of the shoe bottom, said wiper also having an operating surface for continuously wiping the lasting margin inwardly from the edge of the shoe bottom and for pressing it against the shoe bottom.

18. A lasting machine having, in combination, means including a driven roll for tensioning stock to be lasted in a direction heightwise of a shoe and for feeding the shoe, and a rotary wiper for laying the lasting margin of the stock down on and for pressing it against the shoe bottom, said wiper being constructed and arranged relatively to the driven roll so as to press the lasting margin of the stock into frictional engagement with said driven roll at a point located inwardly from the edge of the shoe bottom to cause the roll to draw the lasting margin inwardly over the bottom of the shoe.

19. A lasting machine having, in combination, means including a driven roll, inclined to the plane of the bottom of a shoe presented to the machine, for tensioning stock to be lasted in a direction heightwise of the shoe and for feeding the shoe, and a rotary wiper for laying the lasting margin of the stock down on and for pressing it against the shoe bottom, said wiper being also adapted to hold said lasting margin in engagement with the roll at a point located inwardly from the edge of the shoe bottom to cause the roll to draw the lasting margin inwardly over the bottom of the shoe.

20. A lasting machine having, in combination, means including a driven roll, inclined to the plane of the bottom of a shoe presented to the machine, for tensioning stock to be lasted in a direction heightwise of the shoe and for feeding the shoe, and a rotary wiper having a component of movement inwardly from the edge of the shoe bottom and a component of movement in the

direction of feed for laying the lasting margin of the stock down on and for pressing it against the shoe bottom, said wiper being also adapted to hold said lasting margin in engagement with the roll at a point located inwardly from the edge of the shoe bottom to cause the roll to draw the lasting margin inwardly over the bottom of the shoe.

21. A lasting machine having, in combination, a driven roll and means comprising a rotary disk having a side face for pressing the lasting margin of stock to be lasted against the roll at a point located inwardly from the edge of the bottom of a shoe to cause the roll to exert a frictional drag on the lasting margin in a direction inwardly from the edge of the shoe bottom, said disk also having a peripheral working surface for continuously wiping the lasting margin inwardly from the edge of the shoe bottom and for pressing it against the shoe bottom.

22. A lasting machine having, in combination, a driven roll and means comprising a rotary disk having a flat side face for pressing the lasting margin of stock to be lasted against the roll at a point located inwardly from the edge of the bottom of a shoe to cause the roll to exert a frictional drag on the lasting margin in a direction inwardly from the edge of the shoe bottom, said disk also having a peripheral working surface, formed of a plurality of circumferentially spaced, axially offset, helical ribs, for continuously wiping the lasting margin inwardly from the edge of the shoe bottom and for pressing it against the shoe bottom.

23. A lasting machine having, in combination, a pair of cooperating members for engaging the opposite sides of the lasting margin of stock to be lasted and constructed and arranged continuously and progressively to tension the stock in a direction substantially perpendicular to the bottom of a shoe and to feed the shoe, means for wiping the stock inwardly from the edge of the shoe bottom and for pressing the lasting margin against the bottom of the shoe, and means for heating one of said cooperating members to activate adhesive on the lasting margin before the lasting margin is engaged by said wiping and pressing means.

24. A lasting machine having, in combination, a driven roll, a relatively fixed cooperating member for pressing the lasting margin of stock to be lasted against the roll adjacent to the edge of the bottom of a shoe to cause the roll to apply a frictional drag on said lasting margin for continuously and progressively tensioning the stock heightwise of the shoe and for feeding the shoe, means for wiping the stock inwardly from the edge of the shoe bottom and for pressing the lasting margin against the bottom of the shoe, and means for heating said cooperating member to activate adhesive on the lasting margin before the lasting margin is engaged by said wiping and pressing means.

25. A lasting machine having, in combination, means for continuously and progressively tensioning stock to be lasted in a direction substantially perpendicular to the bottom of a shoe, means comprising a rotary disk having a peripheral working surface provided with helical ribs for wiping the lasting margin of the stock inwardly from the edge of the shoe bottom and for pressing the lasting margin against the bottom of the shoe, and means positioned adjacent to said disk for radiating heat thereto.

26. A lasting machine having, in combination, means for continuously and progressively tensioning stock to be lasted in a direction substantially perpendicular to the bottom of a shoe, means comprising a rotary disk having a peripheral working surface provided with helical ribs for wiping the lasting margin of the stock inwardly from the edge of the shoe bottom and for pressing the lasting margin against the bottom of the shoe, a block having a flat surface positioned close to a side face of the disk and in heat-transferring relation thereto, and means for heating said block.
